COMBINATION AIR CLEANER AND INTAKE SILENCER UNIT

Joseph B. Sebok and Frank Sebok, Detroit, Mich.,
assignors to Houdaille-Hershey Corporation,
Detroit, Mich., a corporation of Michigan

Application December 1, 1947, Serial No. 142,906

Term of patent 14 years

(Cl. D14—6)

To all whom it may concern:

Be it known that we, Joseph B. Sebok and Frank Sebok (full name), citizens of the United States and residents of the city of Detroit, in the county of Wayne and State of Michigan, have invented a new, original, and ornamental Design for a Combination Air Cleaner and Intake Silencer Unit, of which the following is a specification, reference being had to the accompanying drawing, forming a part thereof.

On the drawing:

Figure 1 is a top plan view of the combination air cleaner and intake silencer unit embodying our new design;

Figure 2 is a side elevational view of the structure of Figure 1;

Figure 3 is a bottom plan view of the structures of Figures 1 and 2; and

Figure 4 is a side elevational view of the device taken at 90° to the showing in Figure 2 and from the right-hand side of Figure 2.

We claim:

The ornamental design for a combination air cleaner and intake silencer unit, substantially as shown and described.

JOSEPH B. SEBOK.
FRANK SEBOK.
